METHOD OF AND MEANS FOR UTILIZING
CHARGED-PARTICLE RADIATIONErnest G. Linder, Princeton, N. J., assignor to
Radio Corporation of America, a corporation of
Delaware

Application September 25, 1948, Serial No. 51,206

13 Claims. (Cl. 171—330)

1

This invention relates to electron sources and beams and more particularly to electron beams and multipliers obtained by secondary electrons emitted upon bombardment by nuclear particles.

It is known that certain isotopes are radioactive and emit nuclear charged particles at known rates over known periods of time and over a range of energy values or levels expressed in electron volts. Some emissions consist of positively charged or alpha particles, others of negatively charged or beta particles and others of both alpha and beta particles.

With the emission of a charged particle from the nucleus of an atom, there occurs a transmutation of the atom into an atom of another element and this atom may or may not be radioactive and it may or may not be gaseous in form.

It is also known that when certain materials are subjected to nuclear radiation bombardment, electrons around the nuclei of the bombarded atoms are knocked out of their orbits and projected into space. This phenomenon is known as secondary emission. The number of secondary electrons emitted per bombarding particle depends in general upon the material itself and upon angle of incidence and the velocity of the bombarding particle. In general, the greater the angle of incidence and the less the velocity of the bombarding particle, the greater is the number of secondary emitted electrons.

These secondary emitted electrons usually have relatively low energy values compared with the primary emission values. Their further movements after leaving the bombarded surface depend upon their initial velocities and their initial random direction and upon the electrostatic and electromagnetic fields in the region of motion.

When these secondary electrons strike other secondary-emission responsive materials, further secondary emissions may occur, depending upon the velocity of the electrons and the angles of incidence.

In considering the available radioactive materials, phosphorus³² has been selected to illustrate the invention as it is a pure beta emitter of sufficient average energy for the particles to reach the secondary-emission responsive electrode of the tube and with sufficient energy as to cause secondary electron emission. Also phosphorus³² becomes stable after emission and is particularly adapted to high vacuum tube use as its decay products are not gaseous. There are, however, a large number of other suitable radio-

active substances that may be used within the scope of the invention.

The instant invention comprises improvements on the methods and systems disclosed and claimed in copending U. S. application Serial No. 49,736 filed September 17, 1948, which basic invention contemplates the use of a source of radio-active material and an electrode that is secondary-emission responsive to the charged particle radiation thereof, the space between the source and the electrode being under partial vacuum and also subjected to a constant magnetic field and the source and the bombarded electrode being connected to an external load circuit in which is provided an electric potential source to keep the radio-active source electrode (cathode) positive in respect to the bombarded electrode (anode).

The improvement of the instant invention comprises the addition of an electrode maintained at a high positive potential near one end of the bombarded anode to draw the electrons from their trapped paths and project them in the form of a beam or collect them on the third electrode and thus secure electron multiplication. In both cases the flow of electrons may be modulated to obtain amplification of an electrical modulated source.

Among the objects of the invention are to provide an improved method of and means for producing electron beams.

Another object of the invention is to produce sources of electrons and collect the electrons.

Another object of the invention is to provide an electron multiplier.

Another object of the invention is to provide an electron beam and to modulate the beam in accordance with a signal, such as a source of alternating current or a modulated current.

Another object of the invention is to provide a new method and means for causing secondary emission of electrons.

Other objects may be apparent from the disclosure of the invention as hereinafter set forth in detail and from the drawing made a part hereof in which Figure 1 is a schematic diagram of the said basic invention disclosed in said copending application; Figure 2 is a schematic diagram of the instant invention including a third electrode, such as one near the end of the bombarded electrode; Figure 3 is another schematic diagram of the invention and is similar to Figure 2 except that there is provided a modulated voltage to modulate the electron beam; Figure 4 is a schematic diagram of the invention showing a col-

lector electrode near one end of the bombarded electrode and providing for modulation for the electron beam; and Figure 5 is similar to Figure 4 except the provided modulation is accomplished by a grid positioned between the source of the radioactive material and the bombarded electrode.

Similar reference characters are applied to similar elements throughout the drawings.

Referring to Figure 1, which is a schematic diagram of the basic invention disclosed in said pending application, 1 is a nuclear energy generator tube consisting of a source of radioactive material 2 mounted on a conducting support 3, the source 2 and the support 3 acting as one element of the tube 1.

This element of the tube will be referred to throughout the specification and claims as the "source" or "radioactive source."

The other element of tube 1 is the collector electrode 4, which may be of one of various shapes, shown in this case as a cylinder of sheet material. This electrode 4 is secondary-electron emission responsive upon bombardment by the charged particles emitted from source 2. Aluminum has been found to be a suitable material for electrode 4. An external load 5 is connected between source 2 and electrode 4 and in this load circuit is inserted, in series, a source of electrical potential 6, the positive pole of which is connected to source 2, that the source 2 is positive in respect to electrode 4. Source 2 and electrode 4 are surrounded by an envelope 7 made of some non-magnetic material such as glass and is adapted to exhaustion to a residual pressure of the order of 10^{-3} mm. of Hg or lower by any conventional means, not shown. The residual gaseous medium in the space between source 2 and electrode 4 is subjected to a magnetic field source, illustrated as a solenoid 8 connected to a direct current source 9. Under adjusted conditions of magnetic field and pressure within the envelope, the paths of the secondary emission particles from electrode 4 are lengthened beyond the mean free path for ionizing by collision with molecules of the medium and ionization occurs, making the medium conductive with attending flow of current. The electrons forming this current are supplied by the primary emission of source 2, the secondary emission electrons from electrode 4, and the electrons produced by gaseous ionization, but principally from the latter.

Referring to Figure 2, there are provided a source of radioactive material 2, an electrode 4 in the form of a cylinder of sheet material, a solenoid 8 and a source of direct current 9. There is also provided an electrode 10, which is also shown in the form of a cylinder of sheet material. This electrode 10 will be referred throughout this specification and the claims as the accelerating electrode or accelerator. Accelerator 10 is connected to electrode 4 through a high potential electrical source 14. The electrode 4 is connected to the negative pole of electrical source 6, the positive pole of which is connected to source 2, that the source 2 may be biased and maintained positive in respect to electrode 4. Electrode 4 may be grounded as at 12. The theory upon which the observed amplification of electrons is accomplished by the arrangements disclosed in Figure 1, is not fully known but it is believed to be that when the electrode 4 is bombarded by particles from source 2, and in the absence of a magnetic field therebetween, a current will flow through the external load, con-

nected, for example, to any suitable collector electrode, not shown, which is responsive to the impingement of the beam 13 thereon, as shown in Figs. 4 and 5. Some secondary electrons from electrode 4 will travel to source 2 but, in general, the current through load 5 will be approximately equal to the primary emission current of source 2. When, however, a constant magnetic field is impressed in the space between and parallel to the source 2 and the electrode 4, primary and secondary electrons are deflected in their paths, the primary electrons striking electrode 4 at oblique angles and thus causing a greater secondary emission of electrons than when striking normal to electrode 4 and the secondary electrons being reflected successively by electrode 4, or trapped within the space, until under certain conditions of the magnetic field and the pressure of the medium, the paths of the electrons exceed the mean free path for ionization by collision with molecules of the medium and ionization of the medium occurs, making the medium conductive. This results in an enormous increase in current from the copious supply of electrons made available mainly by gas ionization.

Applying this theory to the instant invention, as disclosed in Figure 2, the copious supply of electrons within the space between the source 2 and electrode 4 are subjected to two forces: (1) the magnetic field created by the solenoid 8 which causes the electrons emitted by secondary emission upon bombardment of electrode 4 by the primary electrons of source 2, as well as the electrons emitted upon bombardment of electrode 4 by the secondary emitted electrons, and also electrons produced by gas ionization to follow curved paths as their velocities are spent and (2) the electrostatic field created by the electric source 14 which sets up a difference of potential between accelerator 10 and electrode 4 and a difference of potential between accelerator 10 and source 2. The electrons are therefore drawn from the space between source 2 and electrode 4 and are accelerated in the form of an electron beam, 13.

Referring to Figure 3, the arrangement disclosed therein is similar to that disclosed in Figure 2, except that the magnetic field is supplied by a permanent magnet 15, on which is disposed the radioactive material 2. Also, in Figure 3, there is included the secondary coil 16 of a transformer, which is connected in series between the biasing electric source 6 and the magnet 15. The negative pole of electric source 6 is connected to the negative pole of electric source 14. The circuit may be grounded as at 12. The primary coil 17 of the transformer is connected to a source of electric potential, either an alternating or a modulated source, such as signal.

In operation, the permanent magnet 15 creates the magnetic field, having a component as shown by arrow H, which deflects the paths of the primary and secondary electrons to trap them in the space between the source 2 and electrode 4, as previously disclosed. The electrons are also subject to the electrostatic field created by the electrical potential 14 and are accelerated as a beam along the axis of accelerator 10.

It is apparent that a variation of the potential impressed on magnet 15 will vary the flow of electrons along beam 13. When the potential of source 2 becomes progressively less positive, electrons are repulsed more and more by the lower electrostatic field around source 2 and more electrons are available to be drawn into beam 13. Also when the potential of source 2

becomes progressively less positive, the electrostatic field between accelerator 10 and source 2 becomes more and more, resulting in an increase of electrons in beam 13.

Referring to Figure 4, the radioactive source 2 is disclosed as concentrated into a small space and mounted on a flat electrode 18, which is positioned opposite electrode 4, which is also in the form of a flat electrode. These elements are mounted in envelope 7. The magnetic field, created by solenoid 8 connected to direct current source 9, is at right angles to the longitudinal axis of electrode 18 and electrode 4, as indicated by H. The magnetic field and the electrostatic field, created by electric source 14, react on the primary and secondary emission electrons and deflect them along the path 19. As the electrons strike electrode 4, at points 20, 20, further secondary emission occurs. There is thus created a copious supply of electrons and the lengths of their paths are increased beyond the mean free path for ionization by collision with molecules of the medium, causing gas ionization and the flow of large currents to the collector plate 21. Collector 21 is connected to electrode 18 through electric source 14, load 5, the secondary coil 16 of a transformer and biasing electric source 6. The drop of potential along load 5 is available for use in an outside circuit (not shown) or the current passing through load 5 may be used in load 5 to perform a useful function. Electrode 4 is grounded at 12 as well as the lead between load 5 and coil 16.

The flow of electrons between electrode 18 and electrode 4 may be modulated in the same manner as disclosed in connection with Figure 3. The secondary coil 16 of a transformer, connected to electrode 18, will impress upon electrode 18 electrostatic potentials in accordance with the alternations or the modulations of currents flowing through the primary coil 17 of the transformer. The potentials on electrode 18 are biased by electrical source 6 connected between coil 16 and the electrode 18.

The disclosure in Figure 5 is similar to that in Figure 4, except that the modulation is accomplished by inserting a grid 22 between the source 2 and electrode 4. Grid 22 is connected to the secondary coil 16 of the transformer, the other end of the coil being connected to the collector 21 through load 5 and electric source 14. The primary coil 17 of the transformer is connected to the source of the modulated current or signal. The electrode 18 is connected through biasing electric source 6 grounded at 12 and to collector 21 through load 5 and electric source 14. Electrode 4 is grounded at 12.

It is apparent that grid 22 will affect the disposition of electrons in the space between electrode 18 and electrode 4, when an alternating or modulating potential is impressed upon the grid by coil 16.

I claim as my invention:

1. The method of utilizing a source of radioactive charged-particle radiation for creating an electron beam comprising: exposing to said radiation a secondary-emission charged-particle radiation responsive material in a confined gaseous medium, subjecting said source and secondary particles to a magnetic field to deflect said source particles against said material at oblique angles and to deflect said secondary particles successively against said material to provide further secondary emission particles and to extend the paths of said secondary particles be-

yond the mean free path for ionization by collision with the molecules of the medium to provide further particles, and impressing on said medium an electrostatic field to accelerate said particles into a beam.

5 2. The method of utilizing a source of radioactive charged-particle radiation for creating and collecting an electron beam comprising: exposing to said radiation a secondary-emission charged-particle radiation responsive material in a confined gaseous medium, subjecting said source and secondary particles to a magnetic field to deflect said source particles against said material at oblique angles and to deflect said secondary particles successively against said material to provide further secondary emission particles and to extend the paths of said secondary particles beyond the mean free path for ionization by collision with the molecules of the medium to provide further particles, impressing on said medium an electrostatic field to accelerate said particles into a beam, and collecting said particles in said beam.

25 3. The method of utilizing a source of radioactive charged-particle radiation for creating and utilizing an electron beam comprising: exposing to said radiation a secondary-emission electron radiation responsive material in a confined gaseous medium, subjecting said source particles and said electrons to a magnetic field to deflect said source particles against said material at oblique angles and to deflect said electrons successively against said material to provide further secondary emission electrons and to extend the paths of said electrons beyond the mean free path for ionization by collision with the molecules of the medium to provide further electrons, impressing on said medium an electrostatic field to accelerate said particles into a beam, collecting said electrons in said beam, and utilizing the currents produced by the flow of said electrons.

45 4. The method of utilizing a source of radioactive charged-particle radiation for creating and controlling an electron beam comprising: exposing to said radiation a secondary-emission electron radiation responsive material in a confined gaseous medium, subjecting said source particles and said electrons to a magnetic field to deflect said source particles against said material at oblique angles and to deflect said electrons successively against said material to provide further secondary emission electrons and to extend the paths of said electrons beyond the mean free path for ionization by collision with the molecules of the medium to provide further electrons, impressing on said medium an electrostatic field to accelerate said particles into a beam, and varying the electrostatic potential of said source to cause variations in the density of said electrons in said beam.

55 5. Apparatus for creating a charged-particle beam including: a radioactive source providing charged-particle emission, means disposed in a region adjacent said source that are secondary-emission charged-particle radiation responsive to said source, said source and said responsive means being disposed in a confined gaseous medium, means for impressing a magnetic field on said source particles to deflect said source particles against said responsive means at oblique angles and to deflect said secondary particles successively against said material to provide further secondary emission particles and to extend the

paths of said secondary particles beyond the mean free path for ionization by collision with the molecules of the medium to provide further secondary charged particles, and means for accelerating said particles into a particle beam.

6. Apparatus for creating and collecting a charged-particle beam including: a radioactive source providing charged-particle emission, means disposed in a region adjacent said source that are secondary-emission charged-particle radiation responsive to said source, said source and said responsive means being disposed in a confined gaseous medium, means for impressing a magnetic field on said source particles to deflect said source particles against said responsive means at oblique angles and to deflect said secondary particles successively against said material to provide further secondary emission particles and to extend the paths of said secondary particles beyond the mean free path for ionization by collision with the molecules of the medium to provide further secondary charged particles, means for accelerating said particles into a particle beam and collecting said particles.

7. Apparatus for creating and controlling an electron beam including: a radioactive source providing charged-particle emission, means disposed in a region adjacent said source that are secondary-emission electron radiation responsive to said source, said source and said responsive means being disposed in a confined gaseous medium, means for impressing a magnetic field on said source radiation particles to deflect said particles at oblique angles against said responsive means and to deflect said electrons successively against said responsive means to provide further secondary electrons and to extend the paths of said electrons beyond the mean free path for ionization by collision with the molecules of the medium to provide further electrons, means for accelerating said particles into an electron beam, and means for varying the electrostatic potential of said source.

8. Apparatus for creating an electron beam including: a radioactive source providing charged-particle emission, an electrode disposed in a region adjacent said source that is secondary-emission electron radiation responsive to said source, the said source and said electrode being disposed in a confined gaseous medium, a solenoid energized from a direct current electrical source disposed adjacent said radioactive source and said electrode, an accelerating electrode disposed adjacent said responsive electrode, an electrical potential source connected between said accelerating electrode and said responsive electrode, and a biasing electrical potential source connected between said accelerating electrode and said responsive electrode, and a biasing electrical potential source connected between said radioactive source and said responsive electrode.

9. Apparatus for creating and controlling an electron beam including: a radioactive source providing charged-particle emission, an electrode disposed in a region adjacent said source that is secondary-emission electron radiation responsive to said source, the said source and said electrode being disposed in a confined gaseous medium, a solenoid energized from a direct current electrical source disposed adjacent said radioactive source and said electrode, an accelerating electrode disposed adjacent said responsive electrode, a collecting potential source connected between said accelerating electrode and said responsive electrode, and a biasing electrical poten-

tial source connected between said radioactive source and said responsive electrode.

10. Apparatus for creating and controlling an electron beam including: a radioactive source providing charged-particle emission, an electrode disposed in a region adjacent said source that is secondary-emission electron radiation responsive to said source, the said source and said electrode being disposed in a confined gaseous medium, a solenoid energized from a direct current electrical source disposed adjacent said radioactive source and said electrode, an accelerating electrode disposed adjacent said responsive electrode, an electrical potential source connected between said accelerating electrode and said responsive electrode, a biasing electrical potential source, and a transformer the primary of which is connected to a source of alternating current and the secondary of which is connected in series with said biasing source between said radioactive source and said responsive electrode.

11. Apparatus for creating and controlling an electron beam including: a radioactive source providing charged-particle emission, an electrode disposed in a region adjacent said source that is secondary-emission electron radiation responsive to said source, the said source and said electrode being disposed in a confined gaseous medium, a permanent magnet disposed adjacent said radioactive source and said electrode, an accelerating electrode disposed adjacent said responsive electrode, an electrical potential source connected between said accelerating electrode and said responsive electrode, a biasing electrical potential source, and a transformer the primary of which is connected to a source of alternating current and the secondary of which is connected in series with said biasing source between said radioactive source and said responsive electrode.

12. Apparatus for creating and controlling an electron beam including: an electrode and a radioactive source mounted thereon providing charged-particle emission, a second electrode that is secondary emission electron radiation responsive to said source and disposed in a region adjacent said source electrode, the said source electrode and said responsive electrode being disposed in a confined gaseous medium, a solenoid energized from a direct current electrical source disposed adjacent said radioactive source and said electrode, an accelerating and collecting electrode disposed adjacent said responsive electrodes and said source, an accelerating electrical potential source, a load, a transformer and a biasing electrical potential source, accelerating source, the load, the secondary coil of the transformer and the biasing source being connected in series with each other and between said collecting electrode and said radioactive source electrode, the primary of said transformer being connected to a source of alternating current.

13. Apparatus for creating and controlling an electron beam including: an electrode and a radioactive source mounted thereon providing charged-particle emission, an electrode disposed in a region adjacent said source that is secondary-emission electron radiation responsive to said source, the said source electrode and said responsive electrode being disposed in a confined gaseous medium, a solenoid energized from a direct current electrical source disposed adjacent said radioactive source and said responsive electrode, an accelerating and collecting electrode disposed adjacent said source and said responsive electrodes, an electrical potential source, a load,

and a biasing electrical potential source, the electrical source, the load, and the biasing source being connected in series with each other and between said source electrode and said collecting electrode, a grid disposed between said source electrode and said responsive electrode, and a transformer the primary of which is connected to a source of alternating current and the secondary of which is connected between said biasing source and said grid.
